BLOW TORCH

David Allen Lenk, Newton, Mass., assignor to The Lenk Mfg. Co., Newton Lower Falls, Mass., a corporation of Massachusetts

Application April 9, 1937, Serial No. 135,873

3 Claims. (Cl. 158—35)

This invention relates to a blow torch and more particularly to a type of blow torch which, when once primed or preheated at its vapor-generating and/or vapor-burning zones, continues to function automatically. Generally speaking, this type of blow torch includes a reservoir for holding a pool of readily vaporizable liquid fuel, such as alcohol and gasoline, leading to a vapor-generating tube from which the fuel vapor is emitted under pressure into a burner tube wherein burning of the vapor takes place as a blast issuing from its outer end and projectible against the work or surface to be heated. There are various ways of feeding raw or liquid fuel from the pool held in the reservoir to the vapor-generating tube, a common one of which involves using a wick that extends from a submerged position in the pool to a position in the vapor-generating tube and thus serves to feed liquid fuel by capillarity from the pool to the internal wall of such tube which, when primed or preheated, progressively generates fuel vapor under pressure from the liquid fuel progressively being supplied thereto.

Heretofore, the practice has been to assemble the blow-torch elements so as to ensure the location of the upper end of the wick at a predetermined or fixed point within the vapor-generating tube, since proper location of such end is requisite for realizing desired fuel vaporization while avoiding scorching or charring of such end. While the use of a rope-like wick of more than sufficient cross sectional area normally to occupy the cross section of the vapor-generating tube makes for some frictional engagement by such wick of the internal tube wall, yet such engagement is not so firm or tight as to obviate dislodgment of the upper wick end, especially when the torch is roughly handled or dropped on a floor. It is possible to increase the cross-sectional area of the wick and to squeeze it more tightly into the vapor-generating tube, but this expedient makes for difficulty of assembly and detracts undesirably from the capillary quality of the wick where it is most needed, namely, where it is supposed to transmit liquid fuel efficiently to the internal wall of the vapor-generating tube.

The present invention affords simple and inexpensive means for maintaining the upper end of the wick in the desired fixed or predetermined position within the vapor-generating tube of a blow torch of the type hereinbefore described while at the same time avoiding undesirable compression of the upper end portion of the wick in contact with the internal wall of such tube. The

means employed herein for such purpose may advantageously take the form of a wire or equivalent elongated member possessed of rigidity or stiffness relative to the wick but capable of being flexed, wherefore, such wire may be associated with the wick in such manner that its lower end is in substantially non-dislodgable engagement with a portion of the internal wall of the reservoir, say, its bottom, and its upper end is in substantially non-dislodgable engagement with the upper end of the wick and holds it substantially fixed even when the blow torch is dropped onto a floor or suffers other shocks in service tending in the absence of such wire or equivalent member to cause undesirable dislodgment of the upper end of the wick.

With the foregoing and other features and objects in view, the instant invention will now be described with particular reference to the accompanying drawing, wherein,

Figure 1 is a largely vertical sectional view of a blow torch embodying the invention hereof.

Figure 2 depicts the wick in assembly with its holder ready for insertion into the torch.

Figure 3 is an enlarged sectional detail through the upper end portion of the vapor-generating tube with the wick and wick-holder properly positioned therein.

Figure 4 is a view similar to Figure 3 showing a modified form of wick-holder.

The torch shown in Figure 1 includes the usual cylindrical fuel reservoir 10 whose bottom 11 has a removable plug 12 for closing a central opening 13 through which liquid fuel, such as alcohol or gasoline, may be introduced into the reservoir for replenishing fuel supply. The bottom 11 may be upwardly convex so that its skirt portion may together with the lower end portion of the cylindrical reservoir wall define an annular pocket or recess 14 whereinto the lower end portion of a wick-holder 15 may be directed so as to make frictional and substantially non-dislodgable engagement with the internal walls of the reservoir, including the internal wall of the bottom 11.

Upstanding from the top of the reservoir is a vapor-generating tube 16 whose lower end portion passes substantially vertically through a bushing 17 having a flanged lower end 17a soldered or otherwise suitably fixed to the reservoir wall bounding the opening therein for receiving the lower end of the bushing. The lower end portion of the tube 16 may project slightly into the empty space 10a normally maintained above the fuel supply 10b whose level is indicated in dash lines. The tube 16 may be frictionally held in the bush-

ing 17 or be soldered or otherwise suitably secured thereto. The external wall of the bushing 17 is shown as carrying threaded thereon a nut 18 for clamping in position against the flange 17a the 5 upper end portion of a handle 19 which is apertured to permit the passage of the tube 16 and the bushing 17 therethrough preparatory to the 10 securing of the nut 18. The handle 19 may be formed of suitable strip metal and be of such 15 curvature that its lower end portion 19a comes close to the reservoir wall.

The upper end portion of the vapor-generating tube 16, which may be inclined at any desired angle from the vertical, carries threaded upon its 15 extremity a closure or cap 20 containing a tiny orifice 21 through which the fuel vapor generated in the tube 16 may issue as a jet. Threaded onto the external wall of the cap 20 may be the usual burner or combustion tube 22 whose wall 20 contains a number of apertures 23 for allowing atmospheric air to enter into the burner tube for 25 promoting complete combustion of the fuel vapor. The vapor-generating tube 16 may be primed or preheated in any suitable way, as by igniting 25 a priming charge of liquid fuel placed in an annular dish 24 resting on the upper end of the bushing 17 and slideable on the tube 16.

The wick 25 for feeding liquid fuel by capillarity from the pool 18b to the internal wall of 30 the vapor-generating tube 16 may consist of a loose bundle of parallel strands or rovings of cotton having very little, if any, twist so as to exercise maximum capillary action. The bundle of rovings or rope-like wick material may, pursuant to the invention hereof, be assembled preparatory to its insertion in the torch with a wick-holder 15 consisting essentially of flexible wire whose upper end portion is in the form of a hook or eye 15a through which the bundle of 35 rovings is threaded, as shown best in Figure 2, to provide a doubled-over wick whose ends terminate at or extend beyond the lower end of the wire. The wick and holder assembly thus prepared may be readily inserted into the upper 40 end of the tube 16 and the wire pushed down along with the wick until its lower end has found its way into the corner or pocket 14. If desired, the ends of the wick may be sufficiently beyond 45 the lower end of the wire 15 to form an accumulation on the bottom of the reservoir. By 50 using wire 15 of the appropriate character, no trouble is had in causing such wire to assume a curvature such that its lower end is trapped frictionally in the pocket 14, but, should any difficulty be encountered in this regard, it is easy to 55 prebend or preshape the wire so that its lower end immediately seeks out the corner 14 as the wick and holder assembly is being pushed down through the tube 16 into the reservoir. The 60 length of the wire 15 is such that once its lower end is brought to rest in the corner 14, its upper end 15a locates the upper end of the wick properly within the vapor-generating tube 16; and, inasmuch as the upper end of the wick is thus 65 fixed in a predetermined desirable position, it does not tend to become charred by reason of being dislodged through shock to a position too close to the burner tube or to generate vapor inefficiently or irregularly by reason of being accidentally displaced to a position too remote 70 from the burner tube.

Ordinary steel wire, such as so-called semi-spring steel wire of about 18 or somewhat greater gauge, is typical of the material of construction 75 satisfactory for the wick-holder hereof. In lieu

of steel wire, it is possible to employ semi-hard brass wire and even ductile metal wire or ribbon, provided that the ductility of the metal wire or ribbon is not so great that it will flex or shift its position in the torch when the torch is roughly handled or suffers impact or shock. In some instances, it may be desirable to use as the wick-holding element multiply wire of appropriate stiffness or rigidity, for instance, twisted multiply wire such as is used for cleaning the stem of a 10 smoker's pipe. Such a twisted multiply element 30 appears in Figure 4 as two intertwined wires whose successive twists or convolutions contain locked therebetween fiber bunches 31 in such density that the exterior aspect is that of a 15 practically continuous fuzzy-surfaced fibrous body. The wick 25 is shown as being looped over the top end of such a multiply wire member 30, which top end serves to stop downward displacement of the wick; and, by virtue of the frictional 20 engagement between the wick and the large aggregate external fibrous surface of the fiber bunches 31 as well as with the internal wall of the burner tube 18, upward displacement of the wick is also practically precluded. It might be 25 noted further that the capillary action of the fiber bunches 31 augments that of the wick proper so as to ensure the desired capillary feed of 30 liquid fuel from the pool in the reservoir to the vapor-generating tube.

It might be noted that the temperature developed in the burner tube wall by continued combustion of such vaporizable fuels as alcohol and gasoline may be in the order of magnitude of 35 about 1600° to 2000° F. A temperature gradient exists inwardly from the outer or hottest end of the burner tube and thence downwardly along the vapor-generating tube, in consequence of which the upper end of the moist wick may be in contact with the internal tube wall surface 40 at sufficiently elevated temperature, say, about 600° to 800° F., to volatilize or flash the liquid fuel practically instantly but yet not so hot as to induce sensible charring of the wick. The wick-holder hereof ensures the maintenance of such 45 desirable location of the upper end of the wick and, being also a good heat conductor, promotes preheating and vaporization of the liquid fuel as it is diffusing by capillarity upwardly through the wicking. The wick-holder hereof is not only 50 simple and inexpensive but does not alter essentially the method of assembling the torch elements or add significantly to the cost of the finished torch.

So far as concerns certain subject matter, this 55 application is a continuation-in-part of my application Serial No. 46,522, filed October 24, 1935.

I claim:

1. In a blow torch, the combination with a reservoir for holding a pool of vaporizable liquid fuel, 60 a vapor-generating tube whose inner end opens into the upper portion of said reservoir, a vapor-burner tube whose inner end communicates with said vapor-generating tube, and a wick which is of loose, rope-like form and extends from a 65 submerged position in said pool to a position, while substantially uncompressed in said vapor-generating tube; of an elongated member which is possessed of rigidity relative to said wick and extends along with said wick from said reservoir 70 into said vapor-generating tube, said member having a lower end existing in substantially non-dislodgable, frictional engagement with the internal wall of said reservoir and having an upper end existing in substantially non-dislodg- 75

able engagement with the upper end of said wick, whereby the upper end of said wick is held by said member in substantially fixed position in said vapor-generating tube even when said blow torch is dropped or undergoes other shock in service tending in the absence of said member to cause undesirable dislodgment of the upper end of said wick.

2. In a blow torch, the combination with a reservoir for holding a pool of vaporizable liquid fuel, a vapor-generating tube whose inner end opens in the upper portion of said reservoir, a vapor-burner tube whose inner end communicates with said vapor-generating tube, and a wick which is of loose, rope-like form and extends from a submerged position in said pool to a position, while substantially uncompressed, in said vapor-generating tube; of an elongated member which is possessed of rigidity relative to said wick but is capable of being flexed and extends in flexed curved condition along with said wick from said reservoir into said vapor-generating tube; the lower end of said member being trapped frictionally in a pocket defined between the skirt portion of the internal bottom wall and the lower end portion of the internal side wall of said reservoir and the lower end of said member existing in substantially non-dislodgable, frictional engagement with the internal bottom wall of said reservoir; and the upper end of said member existing in substantially non-dislodgable engagement with the upper end of said wick, whereby the upper end of said wick is held by said mem-

ber in substantially fixed position in said vapor-generating tube even when said blow torch is dropped or undergoes other shock in service tending in the absence of said member to cause undesirable dislodgment of the upper end of said wick.

3. In a blow torch, the combination with a reservoir for holding a pool of vaporizable liquid fuel, a vapor-generating tube whose inner end opens in the upper portion of said reservoir, a vapor-burner tube whose inner end communicates with said vapor-generating tube, and a wick which is of loose, rope-like form and extends from a submerged position in said pool to a position, while substantially uncompressed, in said vapor-generating tube; of a wire which is possessed of rigidity relative to said wick but is capable of being flexed and extends in flexed curved condition along with said wick from said reservoir into said vapor-generating tube, the lower end of said wire existing in substantially non-dislodgable, frictional engagement with the internal bottom wall of said reservoir and the upper end portion of said wire being in the form of a hook encompassing the upper end portion of said wick, whereby the upper end of said wick is held by said wire in substantially fixed position in said vapor-generating tube even when said blow torch is dropped or undergoes other shock in service tending in the absence of said wire to cause undesirable dislodgment of the upper end of said wick.

DAVID ALLEN LENK.
